US00D779898S

(12) **United States Design Patent** (10) Patent No.: **US D779,898 S**
(45) Date of Patent: **** Feb. 28, 2017**

(54) **APPLICATOR**

(71) Applicant: **OMS Investments, Inc.**, Los Angeles, CA (US)

(72) Inventors: **Randy M. Goodwin**, Grove City, OH (US); **Paul Havlovitz**, Dublin, OH (US); **Ryan R. Berger**, Columbus, OH (US); **Paul Hsu**, Lewis Center, OH (US); **Michael T. Kopczewski**, Grove City, OH (US); **Timothy Michael Martin**, Westerville, OH (US); **Jay F. Perkins**, Pickerington, OH (US)

(73) Assignee: **OMS Investments, Inc.**, Los Angeles, CA (US)

(**) Term: **15 Years**

(21) Appl. No.: **29/532,941**

(22) Filed: **Jul. 13, 2015**

Related U.S. Application Data

(63) Continuation of application No. 29/475,913, filed on Dec. 9, 2013, now Pat. No. Des. 736,577, which is a continuation of application No. 29/433,244, filed on Sep. 27, 2012, now abandoned, which is a continuation of application No. 29/386,483, filed on Mar. 1, 2011, now Pat. No. Des. 670,982.

(51) **LOC (10) Cl.** **08-01**

(52) **U.S. Cl.**

USPC **D8/2**

(58) **Field of Classification Search**

USPC D8/2; D23/224, 225; 239/302, 308, 316, 239/310, 318, 525, 542, 602

CLAIM

The ornamental design for an applicator, as shown and described.

DESCRIPTION

FIG. 1 is a perspective view of an applicator.

FIG. 2 is a front elevation view thereof.

FIG. 3 is a rear elevation view thereof.

FIG. 4 is a side elevation view thereof.

FIG. 5 is an opposite side elevation view thereof.

FIG. 6 is a top plan view thereof; and,

FIG. 7 is a bottom plan view thereof.

The broken line showing of the applicator is included for the purpose of illustrating portions of the article and forms no part of the claimed design.

1 Claim, 6 Drawing Sheets
